Primary Examiner — Bridget L Eland*Assistant Examiner* — Lauren McVey(74) *Attorney, Agent, or Firm* — Philip H. Burrus, IV(57) **CLAIM**

The ornamental design for a medical gown, as shown and described.

DESCRIPTION

FIG. 1 is a front elevation view of a medical gown illustrating our new design; and, FIG. 2 is a rear elevation view thereof.

The long dash broken line between the neck and opening along the back of the gown forms a part of the claimed design. The dot-dash broken lines are directed to environment and form no part of the claimed design. The dot-dot-dash broken lines represent the bounds of the claimed design and form no part of the claimed design.
